UNITED STATES PATENT OFFICE.

GEORGE D. HECK, OF PRINCE BAY, NEW YORK, ASSIGNOR TO THE S. S. WHITE DENTAL MANUFACTURING COMPANY, A CORPORATION OF PENNSYLVANIA.

DENTAL CHAIR.

1,402,292.

Specification of Letters Patent.

Patented Jan. 3, 1922.

Application filed June 14, 1919. Serial No. 304,109.

To all whom it may concern:

Be it known that I, GEORGE D. HECK, a citizen of the United States, and a resident of Prince Bay, in the county of Richmond, 5 State of New York, have invented certain new and useful Improvements in Dental Chairs, of which the following is a specification, reference being had to the accompanying drawings.

10 My invention relates particularly to that class of chairs that are adapted for the use of dentists, barbers or other professional operatives, and is especially directed to the arm-rests that are disposed at the opposite 15 sides of the chair seat.

Chairs of the class contemplated are usually provided with a single standard for the arm-rest connected with the chair frame and engaging the arm-rest intermediate of its 20 ends, thereby leaving the unprotected ends of said arm-rest to catch the clothing, especially the pocket, of the operator.

The object of my invention is to provide an arm-rest with a support so constructed 25 and extended as to shield the projecting end of said arm-rest, and thereby render it incapable of interfering with the free movement of either the operator or the patient in the chair.

30 Specifically stated, the form of my invention as hereinafter described, comprehends an arm-rest support comprising a single standard connected with a chair frame, and having an extension forming a shield, curving rearwardly and upwardly of the rear 35 end of the arm-rest, and arranged to guide the clothing of the operator or of the patient, away from said arm-rest.

My invention also includes all of the various 40 novel features of construction and arrangement as hereinafter more definitely specified.

In the accompanying drawings, Figure 1 is a fragmentary, side elevational view of a 45 dental chair showing the seat, and the preferred embodiment of the arm-rest supported by the seat frame, and Fig. 2 is a similar fragmentary view showing a modification of my invention.

50 In the form of my invention, shown in Fig. 1, the chair frame 1 is supported upon a suitable base 2, and carries the seat 3, leg-rest frame 4, and back-rest frame 5. The arm-rest 6 is carried by the arm-rest sup-

port which is mounted on the seat frame 1, 55 and which comprises a single standard 7, branching into a plurality of upwardly extending members 9 and 10, terminating at their upper ends in the arm-rest plate 12, to which said arm-rest 6 may be attached 60 in any suitable manner.

The member 10 curves rearwardly and upwardly to the rear end of the arm-rest 6 to afford a shield or guard for the clothing of the operator, and is arranged to guide said 65 clothing away from the end of the arm-rest, thus preventing its being caught thereby.

In the form of my invention shown in Fig. 2, the arm-rest 15 is supported by the standard 16, and is provided with a depending shield or guard 17, preferably curving forwardly toward its lower end, and affording a guide to deflect the operator's 70 clothing therefrom.

I do not desire to limit my invention to 75 the precise details of construction and arrangement as herein set forth, as it is obvious that various modifications may be made therein without departing from the essential 80 features of my invention as defined in the appended claims.

Having thus described my invention, I claim:

1. An arm-rest for an operative's chair, comprising a shield affording a guide, depending forwardly from the back end of 85 said arm-rest, and arranged to guide the operator's clothing therefrom.

2. An arm-rest for an operative's chair, comprising a medial support, having a shield 90 affording a guard, curvedly extending rearwardly from said support to the back end of said arm-rest, and arranged to guide the operator's clothing therefrom.

3. An arm-rest for an operative's chair, 95 having a support comprising a single standard branching into a plurality of upwardly extending members, one of which being extended to the end of said arm-rest to form a guard arranged to prevent said arm-rest 100 from catching the operator's clothing.

In witness whereof, I have hereunto set my hand this 12th day of June, A. D. 1919.

GEORGE D. HECK.

Witnesses:
